RADIO RECEIVING SYSTEM

Arthur William Stapleton and Rodney Herbert
Hatfield, London, EnglandApplication January 23, 1935, Serial No. 2,982.
Renewed November 20, 1935. In Great Britain
January 13, 1934

3 Claims. (Cl. 250—40)

This invention relates to radio receiving systems, and has for its principal object to provide a system which automatically adjusts or tunes itself to resonance with any selected carrier wave receivable thereby, whatever may be the frequency, of such carrier wave within the range of the system. Another object is to provide, in a system of this character, means whereby, after the automatic adjusting apparatus has operated to tune the system to any incoming wave, it stops and remains at rest until re-started by the operator.

With the above objects in view, the invention resides in a radio receiving system comprising means active to vary progressively the resonance of the tuned circuit or circuits thereof, means for rectifying radio-frequency signal current in the system, and a relay device responsive to the rectified current therefrom when the system is in tune with respect to an incoming signal to render inoperative the resonance-varying means.

In a convenient form of the invention the system, which preferably incorporates automatic volume control, comprises a variable tuning device or devices for a radio frequency circuit or circuits, a motor having a driving connection with such device or devices for progressively varying the same, and a relay device responsive as above stated for rendering the motor inoperative.

Further objects, features, and advantages of the invention will be apparent on consideration of the following description and attached drawings, which have reference to two of the many practical forms which the invention may take. In the drawings,

Figure 1 is a circuit diagram showing an application of the invention to a "straight" type of radio receiver,

Figure 2 shows an application of the invention to a supersonic heterodyne receiver, and

Figure 3 is a graphical illustration of a feature of operation of the arrangement shown in Figure 2.

In Figure 1, L_1C_1 represents a radio-frequency circuit tunable, by means of the variable condenser C_1 to resonance with an incoming carrier wave of any frequency within a certain range. Oscillations from this circuit are transferred in the known manner, with or without amplification, to the control grid of a rectifying thermionic tube V_1 and the audio frequency currents passed from the anode thereof through a condenser C_2 to an amplifying system at AF.

Now it is well known that the rectified carrier wave appears as a component of the steady anode current of the tube V_1 , being added to or subtracted from the no-signal value of such current according to the characteristics of the grid circuit of this tube. In other words the steady anode current of the tube V_1 rises to a maximum or falls to a minimum when the rectified carrier component reaches its maximum; i. e., when the circuit L_1C_1 and kindred circuits, if any, are correctly tuned with respect to the incoming signal. In the present arrangement there is also incorporated automatic volume control indicated at AVC, according to which a voltage tapped from a resistance R_1 in the cathode lead of the rectifier is incorporated in the grid bias of a preceding radio-frequency tube or tubes to control their sensitivity, the net result being that the maximum or minimum value above referred to of the anode current of the rectifier V_1 is substantially predetermined and independent of the actual weakness or strength of the signal in the aerial system of the receiver.

The anode current of V_1 passes to the high tension source at HT via one winding L_2 of a differentially-wound relay indicated generally at M_1 , the opposed winding L_3 of which is separately energized from the high tension source via a resistance consisting of or including sections R_2 and R_3 . The ends of these sections are connected with a two-pole three-position switch S_1 in such a way that, as is apparent in the figure, R_3 is short-circuited when the switch is in the neutral position shown, R_2 and R_3 are both short circuited when the switch is in one extreme position (down), and R_2 and R_3 are both in circuit when the switch is in the other position (up).

Now the arrangement is such that when R_3 only is short-circuited the field L_3 of the relay is equal, and of course opposite, to that of the winding L_2 when energized by the anode current corresponding to a correctly-tuned carrier wave, consequently according as to whether the switch S_1 is thrown up or down while the receiver is so in tune with a signal the armature A_1 will be moved to one side or the other from its central neutral position.

Reverting now to the tuned circuit L_1C_1 ; the variable condenser C_1 , alone or coupled or "ganged" with corresponding condensers in other tuned circuits, is adapted to be slowly rotated in either direction by a reversible electric motor M through an electromagnetic clutch device indicated generally at D . The device D is such as to throw the motor M into and out of driving

connection with the condenser C_1 when the motor is energized and switched off respectively, and may readily be designed to this end by those versed in the art. For example, the electromagnetic clutch may be operated by a coil or winding connected in parallel with the motor, as shown in the drawings. Or, as an alternative, the motor armature may be longitudinally slideable into and slightly out of its field, being resiliently urged 10 into the latter position as by a spring and bearing one of a pair of clutch plates or friction wheels of which the other is mounted on the condenser shaft. Thus when the motor is energized its armature moves longitudinally to engage the clutch plates or friction wheels, and when it is switched off the reverse movement takes place. In either case, when the supply of current is broken the condenser is instantaneously freed of any overrunning inertia of the 20 armature.

The motor M has permanent or separately excited field magnets, and its armature is energized from a source indicated at B via the contacts of the relay M_1 which, as will be clear from the figure, are adapted to pass current in one direction when the armature A_1 is in one extreme position and in the opposite direction when it is in the other extreme position, all the contacts being open and the motor M de-energized when the 25 relay is in the balanced condition as illustrated.

The operation of the arrangement described in the foregoing is as follows:—

Assuming the rectifier tube V_1 to be operating on the leaky grid principle and the receiver to be correctly tuned to an incoming carrier wave. The switch S_1 is in the intermediate position shown, giving an intermediate value of resistance in the energizing circuit of the relay winding L_3 . The field of the latter balances that of the winding L_2 , which is energized by the steady anode current of the tube V , this current being reduced by the rectified carrier component to the minimum value predetermined by the automatic volume control arrangement.

The armature A_1 of the relay M_1 is thus in the intermediate position shown and the motor M is therefore idle.

If now it is desired to tune the receiver to another carrier wave, the switch S_1 is moved to one or other of its extreme positions to render the field of the relay winding L_3 stronger or weaker than that of the winding L_2 and throw the armature A_1 in one direction or the other, thus starting the motor M to tune the circuit L_1C_1 to a higher or lower frequency as may be desired. When the wanted signal is heard, the switch S_1 is released, the motor M continuing to turn the condenser C_1 until the carrier wave is correctly tuned in, when the steady anode current of the rectifier tube V_1 will have become depressed to the minimum value corresponding to that in the winding L_3 in the intermediate position of the switch S_1 , when the armature A_1 of the relay M_1 moves to the balanced intermediate position, switching off the motor M and simultaneously withdrawing the clutch member D .

It will be realized from the foregoing that solely by movement of the switch S_1 , which may form or be incorporated in a remote-control unit, the receiver may be accurately tuned in to any existing carrier wave which it is capable of receiving, in which respect it is a notable advance on remote control arrangements which are restricted to the selection of one of a limited number of

predetermined resonant frequencies in the radio-frequency circuit or circuits.

It may be observed that in the particular arrangement above described, the motor will always rotate in the same direction when the receiver is off tune with the switch S_1 in the intermediate position, owing to the fact that under these circumstances the field strength of the relay winding L_2 is always greater than that of the winding L_3 , so that when searching in one direction it is necessary to pass through the optimum tuned position when a carrier wave is encountered before releasing the switch S_1 to allow the apparatus to adjust itself to the optimum setting. Where this precaution proves an inconvenience, a modified arrangement may be adopted in which the means for reversing the motor M are associated with the switch S_1 , the relay M_1 being of a simpler type serving only to break the motor circuit, when the anode current of the tube V_1 falls or rises to its minimum or maximum value. Such an arrangement is embodied in Figure 2, in connection with which it will now be more closely described.

In this figure, L_4C_4 and L_5C_5 represent the signal frequency and oscillator frequency circuits tuned by the variable condensers C_4 and C_5 respectively, these condensers being so coupled or "ganged" that the frequency difference between the circuits has always a fixed value, say in the present case 110 kilocycles. Incoming carrier waves are thus converted by rectification, in the known way, to an intermediate frequency of 110 kilocycles and are thereafter treated in a manner analogous to the treatment of radio-frequency signal currents of such frequency in a straightforward receiver.

As in the arrangement of Figure 1, these condensers are simultaneously varied by a motor M through an electromagnetic clutch device D , the motor being energized, when required, from a source B .

In this embodiment of the invention a portion of the intermediate frequency signal current is tapped from the receiver at IF and passed via a condenser C_3 to an intermediate-frequency transformer, indicated generally by T_1 , tuned to 110 kilocycles. The secondary circuit of the transformer T_1 incorporates a quartz or equivalent crystal resonator X . As is well known, such a crystal may be arranged to have an electromechanical resonance period at any predetermined frequency, which in this case will be 110 kilocycles, and has moreover a very high decrement above and below such frequency, in other words is so "sharply tuned" as compared to an ordinary inductance-capacity resonant circuit as to resonate at substantially its natural frequency only. The advantage of this in the present connection is illustrated by Figure 3, in which the full curve shows the voltage-frequency characteristic of an ordinary circuit tuned to 110 kilocycles and the dotted line that of a quartz crystal arranged to resonate at this frequency. It will be apparent that a small variation from the correctly tuned position produces a much greater decrease in the amplitude of the intermediate frequency oscillations passed in the case of the crystal than in the case of the ordinary resonant circuit. In fact it may be said that the crystal will pass a substantial current only when the receiver is correctly tuned, and that it is not therefore essential to employ an automatic volume control arrangement to predetermine the maximum value

of such current, since it is substantially non-existent when the receiver is off tune. A similar effect may be secured, although in a less simple manner, by employing a sharply-tuned filter comprising a plurality of tuned circuits in cascade, and although, as above explained, it is usually not necessary to employ automatic volume control, it may nevertheless be incorporated with advantage.

10 The intermediate-frequency current at 110 kilocycles, after passing the crystal X, is amplified by a screened-grid thermionic tube V₂ and transformer T₂ and rectified by a diode V₃, appearing as a steady voltage across a resistance R₄ in the diode circuit. This voltage is transferred as a negative voltage to the grid of an amplifying-control tube V₄ forming, with an electromechanical relay M₂ in its anode circuit, a relay unit. The arrangement is such that when no appreciable negative voltage is being transferred from the diode V₃ to the grid of the control tube V₄ the normal anode current of the latter is sufficient to hold the armature A₂ of the relay up to the core, the high tension supply to this tube then passing through one of the two closed pairs of contacts of the relay. The other pair of contacts complete the circuit to the motor M, which is thus in the arrangement as illustrated, active to vary the tuning of the receiver.

20 At the moment that the receiver becomes correctly tuned with respect to an incoming carrier wave, the crystal resonator X passes the resulting 110 kilocycle current which is amplified by the tube V₂, rectified by the diode V₃ and is applied 25 as a negative voltage to the grid of the control tube V₄. The anode current of this tube therefore falls sharply in value, the armature A₂ is released, and the two pairs of contacts of the relay M₂ open, breaking the anode circuit of V₄ and 30 the motor energizing circuit respectively.

35 When it is desired to de-tune from the received carrier wave it is only necessary to restore the anode current of tube V₄ to its normal value by short-circuiting the resistance R₄ and shunting 40 the pair of relay contacts through which the anode voltage is applied to the tube V₄. These two operations are conveniently performed by a press-button double-pole single-throw switch S₂, which may be incorporated in a remote-control 45 unit. On pressing this switch the normal anode current will be restored to the tube V₄, the relay M₂ will close and the motor will be started to 50 vary the tuning. The apparatus will immediately be detuned from the carrier wave, and the switch S₂ may be released. The condensers C₄ and C₅ 55 will continue to be progressively varied until another carrier wave is picked up and fully tuned in, when the relay M₂ will release its armature and the motor M be switched off as before. In 60 order to pass over an unwanted carrier wave it is only necessary to hold down the switch S₂ thus preventing the relay system V₄M₂ from being de-energized.

65 In order to reverse the direction of search of the system, or to return to a previous carrier wave, a reversing switch S₃ in the motor energizing circuit is necessary. This may be automatically thrown when the condensers C₄ and C₅ reach their 70 limits of movement, but preferably the reversing

switch S₃ is associated in the remote control unit with the restarting switch S₂.

It is to be noted that the apparatus enclosed by the dotted line in Figure 2 and the remote control unit embodying the switches S₂ and S₃ are particularly well adapted to constitute auxiliary units for connection to or incorporation in existing supersonic heterodyne receivers, and that this is regarded as a valuable and important aspect of the invention.

10 In all cases where a remote-control unit is employed, it may be desirable to incorporate therein means remotely controlled by the variable condensers for indicating the frequency to which the system is tuned at any instant. Such means may 15 readily be devised in a number of ways by competent persons, and it is therefore unnecessary to describe or illustrate the same in detail.

We claim:—

1. In a radio-receiving system, the combination of tuning means, motor means for progressively operating the same, a relay, means for energizing the same comprising a circuit including a pair of contacts, signal receiving means constructed and connected to vary the strength of magnetization of said relay at a moment when incoming signals are in tune with said system, to thereby open said contacts, an energizing circuit for said motor means including contacts held closed so long as the magnetization of said relay 30 is not varied by said signal receiving means and broken by said relay when the magnetization thereof is so varied, and means operable at the will of the operator at any time, and including a circuit shunting said first named contacts, for 35 re-energizing said relay.

2. In a radio-receiving system, the combination of tuning means, motor means for progressively operating the same, a relay, means for energizing the same comprising a circuit including 40 a pair of contacts, signal receiving means constructed and connected to vary the strength of magnetization of said relay at a moment when incoming signals are in tune with said system, to thereby open said contacts, an energizing circuit 45 for said motor means controlled by said relay and broken thereby at the moment when incoming signals are in tune with said system, means whereby said motor energizing circuit remains broken unless closed by a positive act of the operator, and means operable at the will of the operator at any 50 time, and including a circuit shunting said contacts, for restoring said relay to a condition in which it closes said motor energizing circuit.

3. In a radio receiving system, tuning means, 55 means for progressively moving said tuning means to tune said system, means responsive to an incoming signal, when the system is in tune, to stop the motion of the tuning means, said stopping means including a thermionic tube, a relay connected in the plate circuit thereof, and means for impressing on the grid of said tube a voltage derived from the incoming signal, and means, operable at any time at the will of the operator, for causing said relay to restart the motion of 60 said tuning means, said last mentioned means including manual means for altering the voltage impressed on said grid.

ARTHUR WILLIAM STAPLETON. 70
